US0D1047887S

(12) **United States Design Patent** (10) Patent No.: **US D1,047,887 S**
(45) Date of Patent: ** Oct. 22, 2024

(54) **BATTERY**

(71) Applicant: **ZEBRA TECHNOLOGIES CORPORATION**, Lincolnshire, IL (US)

(72) Inventors: **Dae Suk Noh**, Vernon Hills, IL (US); **Ramana Reddy Palpunuri**, Mississauga (CA)

(73) Assignee: **Zebra Technologies Corporation**, Lincolnshire, IL (US)

(**) Term: **15 Years**

(21) Appl. No.: **29/741,842**

(22) Filed: **Jul. 16, 2020**

(51) LOC (14) Cl. **13-02**

(52) U.S. Cl.

USPC **D13/103**

(58) **Field of Classification Search**

Primary Examiner — Christy Nemeth

(57) **CLAIM**

The ornamental design for a battery as shown and described.

DESCRIPTION

FIG. 1 is a first perspective view of a battery of our new design;

FIG. 2 is a second perspective view thereof;

FIG. 3 is a rear view thereof;

FIG. 4 is a front view thereof;

FIG. 5 is a first side view thereof;

FIG. 6 is a second side view thereof;

FIG. 7 is a top view thereof; and,

FIG. 8 is a bottom view thereof.

The broken lines in the drawings are for the purpose of illustrating portions of the article that form no part of the claimed design.

1 Claim, 6 Drawing Sheets
